(57) **CLAIM**

The ornamental design for a rail for an architectural covering as shown and described.

DESCRIPTION

FIG. 1 is a top perspective view of a rail for an architectural covering.

FIG. 2 is a front view of the rail illustrated in FIG. 1.

FIG. 3 is a rear view of the rail illustrated in FIG. 1.

FIG. 4 is a first side view of the rail illustrated in FIG. 1.

FIG. 5 is a second side view of the rail illustrated in FIG. 1.

FIG. 6 is a top view of the rail illustrated in FIG. 1.

FIG. 7 is a bottom view of the rail illustrated in FIG. 1.

FIG. 8 is a bottom perspective view of the rail illustrated in FIG. 1; and,

FIG. 9 is a detail view of a portion of the rail illustrated in FIG. 8.

The dashed or broken lines contained within the figures represent portions of the disclosed subject matter that form no part of the claimed design.

The break lines contained within the figures (and the portions of the rail extending between the break lines) form no part of the claimed design.
